UNITED STATES PATENT OFFICE

JOHN M. OLDHAM, OF DETROIT, MICHIGAN ASSIGNOR TO L. A. YOUNG SPRING & WIRE CORPORATION, OF DETROIT, MICHIGAN

SPRING STRUCTURE

Application filed February 13, 1930. Serial No. 428,041.

The main object of this invention is to provide in a spring structure an improved supporting base which effectively supports the springs and is also well adapted for the attachment of the upholstery thereto.

A further object is to provide a structure having these advantages which may be formed of comparatively light material and at the same time is very strong and rigid.

10 A still further object is to provide a structure having these advantages which is economical to produce and permits the very rapid assembly of the springs and securing of the upholstery.

15 Objects pertaining to details and economies of my invention will definitely appear from the description to follow. The invention is defined in the claims.

20 A spring structure embodying the features of my invention is clearly illustrated in the accompanying drawing in which:

Fig. 1 is a fragmentary perspective bottom view of a spring structure embodying the features of my invention.

25 Fig. 2 is a detail vertical section through a spring structure embodying my invention.

Fig. 3 is an enlarged detail sectional view on line 3—3 of Fig. 1.

30 Referring to the drawing, 1 represents the body springs, only outer body springs being illustrated. The springs are supported by a base frame designated generally by the numeral 2 which is formed of sheet metal folded to provide a channel having inturned flanges 3 and 4 at the top. The flange 4 has an outwardly offset portion 5 overlapping and spaced from the flange 3.

35 The tacking strip 6, preferably of fiber, is arranged within the channel of the frame with the flanges 3 and 4 clamped thereon.

40 The bottom coils 7 of the body springs are arranged between the flanges which contact to form an inwardly facing channel 8 and are secured therein by indenting or clamping down the outer flange thereon as at 9, Fig. 3. This provides a very secure means for attaching the springs to the frame and means which permits rapid assembly of the springs in the frame.

50 The bottom wall of the frame is provided

with a plurality of tacking holes 10, that is, holes through which tacks as 11 may be driven into the tacking strip. The upholstery 12 is provided with a skirt portion 13 which is wrapped upon the frame and secured thereto by tacks driven into the tacking strip. A gimp or finishing strip 14 is preferably provided.

55 The upholstery is thus secured to the under side of the frame so that the securing means is concealed when the cushion is in use.

60 The holes 10 are formed in the frame prior to the bending thereof and, owing to their presence, the frame may be easily bent. While the holes are distorted in the bent 65 portion of the frame as shown in Fig. 1, this does not interfere with their utility.

65 The parts of my improved spring structure are economical to produce, and are very rapidly assembled, both in the matter of securing the springs and in the attachment of the upholstery.

70 I have illustrated only portions of a spring structure and but one embodiment of my improvements as it is believed that this disclosure will enable those skilled in the art 75 to embody or adapt the same as may be desired.

Having thus described my invention what I claim as new and desire to secure by Letters Patent is:

75 1. The combination in a spring structure of the class described with the body springs, of a base frame of sheet metal folded into a channel and having inturned overlapping flanges at the top, the overlapping portion of the outer flange being upwardly offset and spaced from the inner flange providing an 80 inwardly facing channel in which the body springs are disposed and secured by clamping the outer flange thereon, a tacking strip clamped within said frame, the bottom wall of the frame having a plurality of openings therein, and an upholstery covering comprising a skirt portion wrapped upon said 85 frame and secured to the under side thereof by tacks driven into the tacking strip through said openings in said frame.

90 2. The combination in a spring structure with the body springs, of a channeled base 95

frame having inturned overlapping flanges at the top, the overlapping portion of the outer flange being spaced from the inner flange providing an inwardly facing spring supporting channel in which the bottom 5 coils of the body springs are clamped, a tacking strip within the channel of said frame, said flanges being clamped upon said tacking strip, one wall of the frame having a plurality of tacking openings therein, and an upholstery covering tacked to said tacking strip through said openings.

3. The combination in a spring structure, of body springs, a channeled base frame having overlapping flanges clamped upon coils 15 of said springs, and a tacking strip arranged within the frame, one wall of the frame having openings therein through which tacks may be driven into said tacking strip for securing an upholstery covering thereto.

4. A spring structure frame element of channel cross section having inturned overlapping flanges at the top, the outer flange being offset from the inner providing an inwardly facing spring supporting channel, 25 and a tacking strip within said channel, the bottom wall having a series of openings therein through which upholstery tacks may be driven to secure upholstery to said frame.

5. A spring structure, a base frame of sheet metal folded into a channel and having inturned overlapping flanges at the top, the overlapping portion of the outer flange being upwardly offset and spaced from the inner flange providing an inwardly facing 35 channel in which body springs may be secured by clamping the outer flange thereon, and a tacking strip clamped within said frame, the bottom wall of the frame having a plurality of openings therein through which upholstery securing tacks may be driven.

6. A spring structure frame element of channelled cross section having inturned overlapping flanges, the overlapping portion of the outer flange being spaced from the inner flange providing a spring engaging channel, 45 and a tacking strip within the channel of said frame, said flanges being clamped upon said tacking strip, one wall of the frame having a plurality of tacking openings therein.

7. A channeled spring structure frame element having spaced overlapping flanges providing body spring securing means, and a tacking strip arranged within the frame 55 channel, one wall of the frame having openings therein through which tacks may be driven into the tacking strip for securing the upholstery covering thereon.

In witness whereof I have hereunto set my
60 hand.

JOHN M. OLDHAM.
